(57) **CLAIM**

What is claimed is the ornamental design for a magazine guide for a firearm, as shown and described.

DESCRIPTION

FIG. 1 is an elevated front right-side perspective view of a magazine guide for a firearm showing our new design.

FIG. 2 is a depressed rear left-side perspective view of the magazine guide of FIG. 1.

FIG. 3 is a right-side elevational view of the magazine guide of FIG. 1, the left side being a mirror image thereof.

FIG. 4 is a top plan view of the magazine guide of FIG. 1.

FIG. 5 is a bottom plan view of the magazine guide of FIG. 1.

FIG. 6 is a rear elevational view of the magazine guide of FIG. 1

FIG. 7 is a front elevational view of the magazine guide of FIG. 1.

FIG. 8 is an enlarged detail view of the magazine guide of FIG. 2 at location 8; and,

FIG. 9 is another right-side elevational view of the magazine guide of FIG. 1 shown in a position of use on a firearm. The broken dash lines in the form of a firearm in FIG. 9 depict environmental subject matter and form no part of the claimed design. All the other broken dash lines in the figures depict portions of the magazine guide for a firearm that form no part of the claimed design.
